Wesley Glearr
ATTORNEY

UNITED STATES PATENT OFFICE.

VICTOR G. VAUGHAN, OF WILKINSBURG, PENNSYLVANIA, ASSIGNOR TO WESTINGHOUSE ELECTRIC & MANUFACTURING COMPANY, A CORPORATION OF PENNSYLVANIA.

HEATING ELEMENT.

Application filed May 19, 1923. Serial No. 640,057.

To all whom it may concern:

Be it known that I, VICTOR G. VAUGHAN, a citizen of the United States, and a resident of Wilkinsburg, in the county of Allegheny and State of Pennsylvania, have invented a new and useful Improvement in Heating Elements, of which the following is a specification.

My invention relates to electrically heated devices and particularly to electric heating elements for such devices.

One object of my invention is to provide an oxidizable coating for a non-oxidizable resistor.

Another object of my invention is to provide a heating element that shall comprise a resistor of a non-oxidizable material having an electric-insulating coating thereon of a material that oxidizes at relatively high temperature while still retaining its insulating quality.

Another object of my invention is to provide a non-oxidizable resistor having an electric-insulating coating thereon, and means for supporting and holding said resistor in its original normal position in an electricaly-heated device.

In practicing my invention, I provide a supporting member of electric insulating material on which is wound tightly and closely, a helix of an electric resistor, such as nichrome, having a coating of enamel thereon. An external layer of insulating material is tightly wound on a layer of the resistor to hold the turns thereof in their original position after the coating becomes oxidized, due to the relatively high temperature produced during the operation of the heating element.

In the single sheet of drawings,

Figure 1 is a view, in side elevation with certain parts cut away, of an electrically heated device having a heating element embodying my invention,

Fig. 2 is a view in longitudinal section, of a heating element embodying my invention, and

Fig. 3 is an enlarged view, in longitudinal section, of a portion of a heating element embodying my invention.

An electrically heated device 11, which is here represented as a curling iron, comprises a tubular barrel 12, a ferrule 13 and a han-

dle member 14. A removable tong 15 is operatively mounted thereon, a member or button 16, of a suitable heat-insulating material, being provided at the end adjacent to the handle of the curling iron to permit of the operator actuating the tong against a spring member 17, that is effective to yieldingly maintain the tong in close operative engagement with the barrel 12. I have elected to illustrate the device embodying my invention in connection with a curling iron as it has been developed in connection with such device but its use is not restricted thereto.

A heating element structure 18 for the device comprises a central and longitudinally extending metal rod 19 upon which there is mounted a layer 21 of a suitable electric-insulating material, such as mica or micanite, that is adapted to withstand relatively high temperature without deterioration.

A layer 22 of a non-oxidizable resistance material, such as nichrome is wound upon the layer 21. The wire 22 is coated with a layer 23 of a suitable electric-insulating enamel, such as has heretofore been extensively used on ordinary electric circuit conductors of relatively small diameter, where the material of the conductor was usually copper.

The amount of electrical energy that it is desired to translate into heat is relatively small in a curling iron, usually about 15 watts, and it has been customary heretofore, to employ a wire of nichrome of approximately .003" or 3 mils in diameter in order to obtain sufficient resistance to limit the current to such a value on a 110 volt circuit that only 15 watts of energy would be translated into heat. This size of wire permitted the resistor to be so wound as to leave a small space between the adjacent turns, but trouble was experienced in such heating elements by reason of the very small diameter of wire causing it to burn out when subjected to relatively high temperatures.

By providing a coating of enamel on a nichrome conductor that is non-oxidizable, I find it possible to wind the adjacent turns of the resistor in close operative engagement on the electric insulating supporting member 21 and I find it possible therefore to employ a wire of larger diameter. For instance, I employ a wire .005" or 5 mils in

diameter and still obtain substantially the same electrical resistance as was heretofore obtained with the distributed winding of wire of .003" diameter.

- 5 An outer coating 24 of a suitable electric-insulating material, such as flexible mica or micanite is tightly wound around the layer of resistance wire 22. An extended helix 25 of a suitable non-oxidizable wire 10 may be wound around the outer surface of the layer 24 in order to further assist in holding the component parts of the heating element in their proper normal operative positions relatively to each other.
- 15 One end of the resistor 22 is electrically connected to the metal member 19 at the inner end thereof, as indicated by the numeral 25. The other end of the resistor 22 is brought to a terminal member 26 that is 20 so insulatedly mounted on the metal rod 19 at the other end thereof as to lie within the handle 14. That end of the rod 19 located within the handle 14 and the member 26, constitute the terminals of the herein- 25 before described heating element, and a chamber 27 is provided in the handle 14 to permit of the insertion therein of a suitable connector plug for permitting the energization of the heating element in the usual 30 well known manner.

The coating 23 of enamel provided over the entire length of the resistor 22 oxidizes upon the heating element being subjected to the relatively high temperature under which 35 such a device normally operates but the electrical insulating qualities thereof are retained without any appreciable decrease thereof. The mechanical characteristics of the coating change slightly in that the coating 40 becomes relatively brittle, but the coating is maintained in substantially its original position by the layers 21 and 24 of electric insulating material, and further by the fact that the adjacent turns are wound in 45 close operative engagement. The result of this arrangement is that the positions of the turns of wire relatively to each other do not change. By my invention I obtain 50 a heating element comprising a non-oxidizable resistor of greater area of cross-section than I have been able to obtain heretofore, and closely wound relatively to each other, provided with a relatively very thin coating of electric-insulating material which, while 55 becoming oxidized, still retains substantially all of its electric insulating qualities, and which is maintained in its ordinary location around the individual turns of resistor wire under all conditions of operation.

60 While I have illustrated a particular embodiment of my invention, I have done so only as this is the first device to which my invention has been applied, and it is evident that it may be employed in a large 65 variety of devices and permits of obtaining

substantially the same results as I have obtained in the one case. It may be used, for example, in electric warming pads where the temperature is not high enough to cause the coating to become oxidized. In such a 70 device the wire is sewed on a sheet of flexible material and the coating of electric-insulating material affords additional insulation and provides an additional safeguard against damage or burnout in case of 75 accidental contact of two parts of the resistor having an appreciable difference of potential between them.

Various modifications and changes may be made without departing from the spirit 80 and scope of my invention, and I desire, therefore, that only such limitations shall be placed thereon as are imposed by the prior art or are set forth in the appended claims. 85

I claim as my invention:

1. A heating element comprising a non-oxidizable resistance conductor having an oxidizable electric insulating coating. 90

2. A heating element comprising a resistance conductor of a nickel-chromium alloy having an oxidizable electric-insulating coating. 95

3. A heating element comprising a non-oxidizable resistor having an electric-insulating coating of a material that oxidizes at a relatively high temperature. 100

4. A heating element comprising a resistor of a nickel-chromium alloy having thereon an electric-insulating coating of a material that oxidizes at a relatively high temperature. 105

5. A heating element comprising a non-oxidizable resistor having thereon a very thin coating of an electric-insulating material that oxidizes at a relatively high temperature. 110

6. A heating element comprising a resistance conductor that is non-oxidizable at a relatively high temperature and having a coating of electric-insulating material that oxidizes at that temperature. 115

7. A heating element comprising a supporting means of electric-insulating material, a non-oxidizable resistance conductor having an oxidizable electric-insulating coating wound on said supporting means, and an outer cover member closely surrounding said resistance conductor. 120

8. A heating element comprising a supporting means of electric-insulating material, a non-oxidizable resistance conductor having an electric-insulating oxidizable coating wound on said support with the adjacent turns thereof in close operative engagement, and means located outside of said winding of resistance conductor for holding the turns of said winding in proper operative positions relatively to each other. 125

9. A heating element comprising a sup-

porting means of electric-insulating material, a non-oxidizable resistance conductor having a coating thereon of an electric insulating material that oxidizes at relatively high temperature tightly and closely wound on said supporting means, and an external layer of electric-insulating material for

holding said conductor in its initial position after oxidation of said coating.

In testimony whereof, I have hereunto subscribed my name this 15th day of May, 1923.

VICTOR G. VAUGHAN.
